Otto Hallbauer, Teaneck, N. J.

Application October 24, 1942, Serial No. 108,606

Term of patent 3½ years

To all whom it may concern:

Be it known that I, Otto Hallbauer, a citizen of the United States, residing at No. 1134 Laurelton Parkway E, in the city of Teaneck, West Engelwood Division, county of Bergen, and State of New Jersey, have invented a new, original, and ornamental Design for an Embroidered Trimming or Similar Article, of which the following is a specification, reference being had to the accompanying drawing, forming a part thereof.

The figure is a plan view of an embroidered trimmed or similar article showing my design.

I claim:

The ornamental design for an embroidered trimming or similar article, as shown.

OTTO HALLBAUER.
